STETHOSCOPE CHESTPIECE

David Littmann, Belmont, Mass., assignor to Minnesota
Mining and Manufacturing Company, Maplewood,
Minn., a corporation of Delaware

Filed Apr. 9, 1968, Ser. No. 11,372

Term of patent 14 years

U.S. Cl. D83—12
Int. Cl. D24—03

FIG. 3

FIG. 1 is a top plan view of a stethoscope chestpiece embodying my invention;

FIG. 2 is a bottom plan view; and

FIG. 3 is a side view looking from the left of FIG. 1. The opposite side to that shown in FIG. 3 is the mirror image of FIG. 3.

I claim:

The ornamental design of a stethoscope chestpiece, as shown and described.
